MATCH PACKAGE

Samuel Milone, Camden, N. J., assignor, by direct and mesne assignments, of thirty-one and one-fourth per cent to Franklin R. Cawl, Rosemont, Pa., and thirty-one and one-fourth per cent to Barrie Weiss, Philadelphia, Pa.

Application May 2, 1935, Serial No. 19,508

6 Claims. (Cl. 206—33.4)

My invention relates to the so-called book matches, that is to say, match packages that include a cover within which the matches in a cluster are secured and from which a match at a time may be removed for lighting. Usually the cover which is of cardboard includes a hinged flap that must be opened to give access to the matches for their removal one by one. An object of my invention is to provide a match package differing in the particular that no cover must be opened to give access to the matches and which must thereafter be closed and yet the matches while completely protected by a suitable enclosure may easily or readily be withdrawn from the package one at a time for ignition. Other objects of my invention are to provide a match package having the characteristics just mentioned which will be unique and attractive in appearance and in the manipulations required to obtain a match for lighting and which will afford considerable space or area for advertisements which are so important a feature of match packages. Other objects and advantages will appear from the hereinafter given detailed description or explanation of various embodiments of my invention shown in the drawing.

My invention consists in whatever is described by or is included within the terms or scope of the appended claims.

30 In the drawing:

Figs. 1 and 2 are, respectively, front and back views of a match package embodying my invention, a match being shown in position in Fig. 1 ready for removal;

35 Fig. 3 is a section on the line 3—3 of Fig. 1;

Fig. 4 is a view in section of an embodiment of my invention suitable for the use of refills without discarding the cover;

Fig. 5 is a front view of a refill construction of 40 the vanity case type with the cover made attractively of sheet metal;

Fig. 6 is a side elevation of the case alone shown in an open position;

Fig. 7 is a plan view of a portion of the back 45 of the case shown in Figs. 5 and 6;

Fig. 8 is a view in perspective of an embodiment of my invention that includes an ash tray.

Briefly described, the various embodiments of my invention illustrated in the drawing include 50 a shallow case or cover with spaced apart front and back, and a disc-form match carrier rotatably mounted in the shallow space thus provided within the cover and which supports or has attached to the side thereof matches that radiate from the center with their heads outermost, the

rim or periphery of the carrier being accessible at the rim of the casing, for contact of the finger or fingers of the hand so that the carrier and the circular group of matches thereon may be rotated to present the headed ends of the matches successively at an opening in the side wall of the case for ready removal of a match and without the necessity of opening the case or cover for that purpose. An important feature of the invention in each of the embodiments thereof shown in the drawing is the automatic protrusion or projection of the headed portion of a match when it comes to or opposite said opening sufficiently away from the adjacent matches to enable the grasping by the fingers of the headed part of such match for removal or detachment from the carrier. It will be observed that all matches within the case or cover at all times are wholly covered and protected from accidental ignition as by the striking of a detached match for even at the time one match is presented for removal, the heads of all other matches are covered by the casing walls.

Describing in detail what is shown in Figs. 1 to 3, the case or cover has a disc-form front wall 10, and a disc-form back wall 11, which conveniently may be made by cutting from a single sheet of cardboard with an integral narrow tongue or web 12, joining them through a limited extent of their peripheries which contributes to holding them in fixed relative positions when as shown in Fig. 3, they are folded over in spaced apart parallel relation to provide room to accommodate disc-form match carrier 13, and the circular group or cluster of matches 14, secured to one side of said carrier 13. The carrier 13 is of sufficiently greater diameter than the discs which form the front and back of the cover that, as shown in Figs. 1 and 2, it projects beyond the cover rim so that it may be engaged by the finger or fingers and revolved on a pivot 15, at the center of the 40 cover. Preferably the projecting rim of the carrier 13 is gently serrated to assure sufficient grip of the finger thereon to rotate it. The pivot 15 may be held in place by a suitable fastener that passes through it and through the opposite front 45 and back walls of the cover and thereby the parts held in proper relative position even under force applied to the carrier 13 to rotate it.

As well shown in Figs. 3 and 4, the match splints slant slightly away from the carrier 13, so that 50 their head portions are spaced therefrom, so that the inner pointed or sharpened end of a tongue 16, that extends from the outer wall into the cover, may engage the splint as the splint rotates with the carrier and the headed end of the match 55

thereby be lifted to present it at a radially extending hole or slot 17, in the front wall of the cover opposite the lifting tongue 16. Said tongue may conveniently be formed by cuts at three 5 sides which leave it attached at one side or edge to the front wall and permit it to be pushed or forced downward at the desired incline into the path of matches.

On the outside of the back wall 11, a match 10 striking or scratch surface 18, in the form of an oblong area of suitable extent may be provided and adjacent one edge thereof is hinged a flap 19, of oblong form that may be turned on such edge to pinch an interposed match head against the 15 striker surface so as to insure the ignition thereof when drawn between the adjacent surfaces. Such flap 19 may conveniently be formed by cuts on three edges that sever it at such edges from the cover back and at the same time provide a 20 rectangular window or opening 20, through which when the flap is turned over, the side surface of the match carrier opposite that which the matches are secured will be exposed, and upon such carrier surface may be placed advertising 25 matter which is brought to view by the turning of the carrier. This enables the utilization of such carrier surface for advertisement, and, of course, advertising matter may be placed upon the outer side of the back as well as the front walls of the 30 case. And, of course, the surfaces of the match sticks or splints are available for advertisements and as the splints by reason of their circular and radial arrangement may be an outwardly enlarging or tapering shape, such outer surfaces of the 35 splints provide a substantial area for advertisements. The splints may be formed from a disc of heavy paper or cardboard separated from one another at the sides by radial cuts or incisions. The splints may be separately formed and 40 cured as by gluing to the carrier.

Referring to Fig. 4, an inexpensive refillable type of match package is shown. Like the case or cover of Fig. 1, it comprises a case or cover with a front 100, and a back 110, joined by a narrow 45 connection 120, which constitutes a hinge on which the backing cover may be opened as shown in Fig. 4, for placing therebetween the refill consisting of rotatable carrier 130 and matches 140. To provide the connection between the parts for 50 use when the front and back are moved to positions parallel and the pivot on which the match carrier and matches may be turned, the complementary members 21 and 22 of an ordinary snap fastener may be employed.

Referring to Figs. 5 and 6, a vanity case type 55 of cover may be employed with front 101 and back 111 joined at their peripheries by a hinge 121, a common spring latch 23, being provided at the diametrically opposite edge of the back 111 to snap or catch over the opposite edge of the 60 front 101 at the center. The back 111 has a circular boss or projection 24 on its inner face to provide the pivot for the rotatable match carrier. The front of the case is slotted or cut to provide 65 the match raising tongue 160 and the back 111 has a roughened or ridged, or beaded oblong striker surface 180, over which extends a straight light spring 190 fastened at one end under which the match to be lighted is placed and by which the 70 desired pressure against the scratch surface is obtained to light the match.

As shown best in Fig. 5, only a portion of the 75 periphery of the match carrier 131 need be exposed and small portions thereof may be exposed at diametrically opposite side edges by slabbing

off portions of the circular case so that at other points of the periphery of the case, it will be closed.

As shown in Fig. 8, a match package embodying 5 my invention may be a part of an ash tray. As shown in Fig. 8, the match package is of the vanity case type shown in Figs. 4 and 5, mounted in a vertical position at one side of the tray.

Provision is made for the replacement of a 10 striker strip which is apt to be worn, and this is particularly desirable in the case of the refill type 15 embodiments of my invention. Accordingly, an additional striker strip is supplied that may be substituted for an old one.

Suitable provision is made for the ready or easy 15 attachment of the additional striker strip to the cover.

What I claim is:

1. A match package comprising a holding member with a match receiving space, a plurality of matches within such space, means pivoting the matches as a unit in such space for bodily rotation therein, and means for bodily rotating the matches having a peripheral finger contacting surface accessible at the periphery 25 of the holder, said holder having a side wall perpendicular to the unit pivot, such side wall having a match outlet for matches presented thereto in succession and a match lifting tongue that is stationary and adjacent such outlet in 30 the path of rotation of matches of the unit.

2. A match package comprising a holding member with a match receiving space, a plurality of matches within such space, means pivoting the matches as a unit in such space for 35 bodily rotation therein, means for bodily rotating the matches having a peripheral finger contacting surface accessible at the periphery of the holder, said holder having a match outlet for matches presented thereto in succession, and a 40 stationary match engaging lifting tongue adjacent such outlet in the path of rotation of the matches of the unit.

3. A match package, comprising a collection of matches, a case, means rotatably supporting the 45 collection of matches in the case for bodily movement therein, the case having a match outlet to which, by such bodily movement the matches may be presented successively, and a match lifting tongue adjacent such outlet, having a free 50 end in position to engage an approaching match, under which tongue the match by its movement passes.

4. A match package comprising a rotatable 55 match carrier and matches carried thereby in a circular group with their heads outward, the matches lying flatwise, and a case that includes at one side of the group of matches, a flat wall with an opening in its side, situated in the path of the head portions of the matches, and a stationary tongue projecting inward from said wall in the path of the head portions of the matches as they rotate in the case.

5. A match package comprising a rotatable 65 match carrier and matches carried thereby in a circular group with their heads outward, and a casing with opposite walls movable relative to one another from a closed position, and means normally holding such walls in closed position, 70 said walls lying flatwise over the circular group of matches, one of said walls having in its side an opening situated in the path of the head portions of the matches in their rotation, and means at such opening acting, upon contact of a match 75

therewith as it rotates, to pass the head portion of the match outward through the opening.

5. A match package, comprising a holding member with a match receiving space, a plurality of matches placed flatwise within such space, means joining the splint portions of the matches for bodily movement of the plurality of matches in said space of said holding member, and which joining means allow lateral movement
10 of individual matches crosswise of the path of

bodily movement of the matches, and automatic means including an element adjacent the path of movement of the matches in position when a match comes thereat to press a portion of such match to the outside of the holding member, such match being thereby rendered accessible for grasping by the fingers to remove it from the holding member.

SAMUEL MILONE.
